CLAIM

We claim the ornamental design for a shoe, as shown and described.

DESCRIPTION

FIG. 1 is a front, left perspective view of a shoe, showing our new design;

FIG. 2 is a front, right perspective view thereof;

FIG. 3 is a left side view thereof; and,

FIG. 4 is a front view thereof.

The broken lines adjacent to the shaded area represent boundaries of the claimed design and form no part thereof. The broken lines depicting the remainder of the shoe show features that form no part of the claimed design.
